ROTARY MOTOR, PUMP, AND THE LIKE

Frank A. Talbot, Baltimore, Md.

Application September 11, 1942, Serial No. 458,019

5 Claims. (Cl. 103—136)

1

This invention relates to improvements in rotary motors, pumps and the like, and more particularly to such structures when provided with a rotor having sliding vanes which move inwardly and outwardly relatively to the central portion of the rotor.

One of the objects of the invention is to provide a structure of this character which may reverse the flow of the fluid while the rotor is travelling in a single direction.

A further object is to furnish a motor having a rotor that may be reversed while the motivating fluid flows in a single direction.

Another object is to provide a structure of this type, whereby the speed, if the device is used as a motor, may be controlled to vary the speed between idling and maximum, and this may be accomplished while the motor is travelling forward or in reverse.

A further object is to supply a pump having variable delivery means which may be varied from no flow to maximum, and which may reverse the flow without change of rotation of the rotor.

A still further object is to provide such a structure in which the vanes are pushed outwardly by a pressure fluid within the rotor, and in which the interior of the rotor communicates with the fluid conducting passageways by such means that the vanes will be pushed outwardly regardless of whether the pressure fluid is in one fluid conducting passageway or the other.

Another object is to provide a rotary motor, pump or the like which may be manufactured at a minimum cost because the parts are so shaped that they may be readily manufactured with comparatively few machining operations.

A further object is to produce a simple and durable structure and one which will be exceedingly effective for the purposes for which it is designed.

With the foregoing objects outlined and with other objects in view which will appear as the description proceeds, the invention consists in the novel features hereinafter described in detail, illustrated in the accompanying drawings, and more particularly pointed out in the appended claims.

In the drawings:

Fig. 1 is a top plan view of my improved rotary motor, pump or the like.

Fig. 2 is a front view with the cover plate removed.

Fig. 3 is a vertical sectional view, partly in elevation.

2

Fig. 4 is a view similar to Fig. 2, with the rotor and shiftable ring also removed.

Fig. 5 is a front elevation, partly in section, of a modification, and illustrating one means for balancing the shiftable ring in the casing.

Fig. 6 is a view like Fig. 5, but illustrating another embodiment of the invention.

Fig. 7 is a side elevation of a detail of a pair of the vanes and a positioning ring which normally holds them in an extended position.

Fig. 8 is an elevation of a modification taken at right angles to the view in Fig. 7 and showing a pair of positioning rings used with the vanes.

Fig. 9 is a perspective view of a pair of the vanes of the type shown in Fig. 8.

Referring to the drawings, 10 designates a housing, preferably circular, having a chamber 11 in one face thereof, closed by a cover plate 12 secured in position by any suitable means such as screws 13. The housing and cover plate are provided with confronting circular recesses 14 and 15 to accommodate the ends of a circular rotor 16.

A shaft 17 is rotatably mounted in bushings or anti-friction bearings 18 and 19 arranged respectively in the housing and cover plate, and the shaft is preferably provided with splines 20 which are interlocked with grooves 21 in the hub of the rotor, the grooves being of greater depth radially than the splines in order to permit a fluid to enter a circular chamber 22 within the rotor from a passage 23 in the housing.

The rotor travels in a substantially circular chamber 24 in a ring 25 that is shiftable up and down in the chamber 11, the ring being provided at opposite sides thereof with straight surfaces so that it may slide up and down on tracks 26.

The circular chamber 24, as best shown in Figs. 2 and 4, communicates at all times with fluid conducting passageways 27 and 28, each passageway extending through one side of the housing and opening into the rear of the chamber 11 in which the shiftable ring 25 is located. Such ring may be shifted by any suitable means, as will be hereinafter explained in connection with Figs. 5 and 6.

The rotor, as best shown in Fig. 2, is provided with a series of radial slots 29 extending from its internal chamber 22 to its periphery, and each slot functions as a guideway for a pair of inwardly and outwardly movable vanes, the vanes of each pair being numbered respectively, 30 and 31. While these vanes may be identical in construction, the outer end of each is provided with an inclined or pointed edge, one of these edges

being at one side of the pair, and the other at the opposite side, so that the edges will function as a seal, regardless of the direction of rotation of the rotor. Such edges constantly engage a substantially circular track 33 formed at the interior of the shiftable ring. Owing to the substantially circular shape of the track 33, there will be no movement of the vanes toward the axis of the rotor while the vanes are between the parts 27 and 28 when the ring 25 is at an intermediate position between the neutral and its maximum position either upwardly or downwardly. The inner ends of the vanes are preferably rounded and are engaged by a positioning ring 34 which may be of resilient material. Such ring functions to maintain contact between the vanes and the track 33, and will hold the vanes in such position, even though there is no fluid within the structure.

As shown in Figs. 3 and 4, the passageway 23 is in communication with a conduit 35 which extends transversely of the housing and has its ends in communication with vertical passageways 36 and 37 which communicate respectively with the fluid passageways 27 and 28. Spring pressed ball check valves 38 and 39 control respectively the passage of fluid from either of the passageways 36, 37, while preventing it from going through both of said passageways. In explanation it will be observed that fluid can flow to the interior of the rotor from 27 through 36, 35 and 23, while being prevented from entering the passageway 37 by the check valve 39. On the other hand, if the fluid flows from 28 through 37, 35 and 23 to the interior of the rotor, the check valve 38 will prevent it from passing through 36. As will be hereinafter explained, this allows a pressure fluid to enter the hub of the rotor and to force the vanes radially outward, regardless of the direction of rotation of the rotor, and regardless of whether the passageway 27 or 28 is conducting the pressure fluid.

The passageways 27 and 28 also communicate respectively with drainage passageways 40, 41 which in turn communicate with a lower transverse passageway 42. Check valves 43 and 44 control respectively the passage of drainage fluid from 42 to either 40 or 41. Passageway 42 communicates by means of a duct 45 with the interior of the chamber 11, and by means of a passageway 46, with one end of the bushing 18. In this way, any lubricant used in lubricating the parts, and which may seep along the shaft in one direction, may be discharged from the machine. Another duct 47 will serve to discharge lubricant from the bushing 19 to the chamber 11, from which it may be drained through 42 to either one of the passageways 40 or 41.

From Fig. 3 it will be noted that a circular groove 48 communicates with the chamber 11, so that any fluid or lubricant which may leak into the chamber 11, past the ring 25, will be readily drained and will not interfere with the shifting of such ring vertically.

Assuming the device is used as a pump, 27 may be the intake, and 28 the discharge passageway. Assuming the shiftable ring 25 in Fig. 2 is in the position shown in that figure, and the rotor is travelling in a clock-wise direction, it will be obvious that the vanes 30, 31 will cause fluid to be drawn into 27 and thence into the chamber 24 of the shiftable ring, and as the rotor travels, such fluid will be forced from such chamber through the discharge passageway 28. At such time, the

V-shaped edge of the vane 31 of each pair, will form a tight seal with the track 33.

If the device is used as a motor, of course, the driving fluid will enter through 27, and may be exhausted through 28.

Whether the device is used as a pump or a motor, it will be obvious that its capacity may be varied by simply shifting the ring 25 vertically, and when it has been moved to a neutral position, in which the track 33 is concentric with the periphery of the rotor, the latter will turn without doing any work whatsoever. When the ring is in neutral position, if the device is used as a pump, it will cease pumping, and if used as a motor, it will simply be idle.

If the ring 25 is shifted upwardly beyond neutral position, then the device reverses itself, while the rotor continues to rotate in the same clockwise direction. Assuming the ring 25 is in its uppermost position, and the device is used as a pump, it is evident that the fluid will be drawn in through 28 and be discharged at 27, or if used as a motor, 28 will be the intake and 27 the exhaust.

In order that the pressure fluid will pass to the interior of the rotor for the purpose of forcing the vanes outwardly regardless of whether the ring is up or down, I have provided the passageways 23, 35, 36 and 37. If the device is used as a pump, 25 and 28 is the outlet, the pressure in this passageway, 37—35—23 will be greater than in the passageway 27. Consequently, the pressure fluid will travel to the interior of the rotor through 37, 35 and 23. On the other hand, if the ring 25 is shifted so that 27 becomes the outlet, and 28 the intake, then the pressure fluid will travel to the interior of the rotor through 26, 35 and 23. Of course, similar action will take place when the device is used as a motor.

By means of the passageways 40, 41 and 42, and the check valves 43 and 44, drainage also takes place regardless of whether 27 or 28 is the intake or outlet. In this connection, it is apparent that one of the check valves 43, 44 will always shut off communication with the high pressure side, while permitting drainage to the low pressure side.

When the device is in operation, pressure within the ring 25 may tend to force the ring radially toward one side or the other, depending on the position of the ring, and this might interfere with the shifting of the ring vertically. Therefore, in order to facilitate movement of the ring, I may employ rocking plates 50 as illustrated in Fig. 5. Each of these plates is preferably provided with rounded ends which fit respectively in rounded cavities 51 and 52 arranged respectively in the housing 10a, and the ring 25a. I preferably employ a pair of these plates at each side of the ring.

The ring may be controllably shifted by any suitable means, for example, by a rod 53 which extends in a sealed manner, as at 54, in the housing and is secured at its inner end 55 to the ring.

In the modification shown in Fig. 6, the ring 25b contacts at its opposite sides with, and is guided by anti-friction rollers 56 which tend to keep the ring centered and facilitate its movements.

In any form of the invention, the ring may be held in one position by means of an adjustable spring 57 arranged at one side thereof, and may be moved to other positions by means of a cam 58 which engages the diametrically opposite side

thereof. Such cam may be fixedly secured to a shaft 59 that is rotatably mounted in the housing.

Referring to Figs. 8 and 9, it may be seen that the vanes 30a and 31a of each pair may be identical, but arranged in reversed positions to make up a pair. Each vane may have at its inner end a deep step 60, and a notch 61, the latter accommodating the positioning rings 34a and 34b. The ring 34a will cooperate with all of the vanes 31a, while the ring 34b will coact with all of the vanes 30a. By this means, the V-shaped edges of the vanes will coact in a sealing manner with the track 33 regardless of the direction of rotation of the rotor, and regardless of the position of the ring 25, 25a, 25b.

Two structures of the character above described may be hydraulically connected to achieve desirable results. In such a hook-up fluid forced by one rotor could be used to drive the other rotor, and either or both structures can be variable and/or reversible to obtain maximum speed and torque variations in a speed control device.

From the foregoing it is believed that the construction, operation and advantages of the invention may be readily understood, and I am aware that changes may be made in the details disclosed, without departing from the spirit of the invention, as expressed in the claims.

What I claim and desire to secure by Letters Patent is:

1. A reversible pump or motor comprising a housing having an internal chamber and a pair of confronting recesses arranged at opposite ends of the chamber and communicating therewith, a rotatable shaft extending into said chamber, a cylindrical rotor secured to said shaft, extending through the chamber and having its ends journaled in said recesses, diametrically opposite substantially semi-circular arcuate ports in the housing, concentric with the rotor and opening into the chamber at the periphery of the rotor, a rigid ring movably mounted in the chamber and surrounding said rotor, said ring having a substantially circular internal track which when the ring is in neutral position, is substantially concentric with the periphery of the rotor, said ring being shiftable in the chamber lengthwise of the ports so as to place said track eccentrically relative to the rotor whereby a crescent shaped chamber may be provided between the rotor and ring at either one of two diametrically opposite sides of the rotor, said rotor being provided with substantially radial slots of the same width as the chamber, vanes slidably mounted in said slots and extending across said chamber, yielding means for maintaining the outer ends of the vanes in contact with said track, said rotor having a hub chamber between its ends, into which the inner ends of the vanes extend, and a valved controlled passageway arranged within the housing and placing said hub chamber in communication with said ports whereby a pressure fluid may be introduced into the hub chamber from either of said ports while cut off from the other, for forcing the outer ends of said vanes into contact with said track.

2. A reversible pump or motor comprising a housing having an internal chamber and a pair of confronting recesses arranged at opposite ends of the chamber and communicating therewith, a rotatable shaft extending into said chamber, a cylindrical rotor secured to said shaft and having a central chamber, extending through the chamber and having its ends journaled in said recesses, diametrically opposite substantially semi-circular

arcuate ports in the housing, concentric with the rotor and opening into the chamber at the periphery of the rotor, a rigid ring movably mounted in the chamber and surrounding said rotor, said ring having a substantially circular internal track which when the ring is in neutral position, is substantially concentric with the periphery of the rotor, said ring being shiftable in the chamber lengthwise of the ports so as to place said track eccentrically relative to the rotor whereby a crescent shaped chamber may be provided between the rotor and ring at either one of two diametrically opposite sides of the rotor, said rotor being provided with substantially radial slots of the same width as the chamber of the rotor, vanes slidably mounted in said slots and extending across the chamber, fluid conducting passageways in the housing communicating with said ports, other passageways placing said fluid conducting passageways in communication with the central chamber of the rotor for conducting pressure fluid to the slots for forcing the vanes outwardly, check valves in the housing controlling said other passageways for causing the pressure fluid to enter the rotor from either one of the fluid conducting passageways and to cut it off from the other when the pressure of the fluid in either one of the conducting passageways is higher than in the other, all of the passageways being entirely within the housing, and resilient means arranged in the rotor and contacting the inner ends of all of the vanes for constantly maintaining the outer ends of the rotor in contact with said track.

3. In a structure of the character described, a housing having an internal chamber, a rotatable shaft extending into said chamber and provided with splines, a substantially cylindrical rotor secured to said shaft and having grooves into which the splines extend, said rotor having closed ends with an internal chamber between them, at least some of said grooves being of greater depth than the splines which occupy them to provide a passageway through which a pressure fluid may be introduced into the internal chamber of the rotor, a circular track surrounding the rotor, said rotor being provided with radial slots, vanes slidably mounted in said slots and having their inner ends subject to pressure within said internal chamber and their outer ends in contact with said track, and fluid conducting passageways opening into said chamber at one end portion of said rotor and at diametrically opposite sides of said track.

4. In a structure of the character described, a housing having an internal chamber, a rotatable shaft extending into said chamber, an approximately circular rotor secured to said shaft, a shiftable ring arranged in said chamber and surrounding the rotor, said ring having a substantially circular track which when the ring is in a neutral position, is substantially concentric with the periphery of said rotor, fluid conducting passageways opening into said chamber at one end portion of said rotor and at diametrically opposite sides of said ring, said rotor being provided with radial slots, vanes slidably mounted in said slots, and means in said internal chamber to facilitate movement of the shiftable ring to prevent the same from binding when it is moved, the last mentioned means comprising oppositely disposed cavities in the housing and ring, and thrust plates each having one of its ends movably mounted in

a cavity of the housing and its other end movably mounted in a cavity of the ring.

5. In a structure of the character described, a housing having an internal chamber, a rotatable shaft extending into said chamber, substantially circular rotor secured to said shaft, a shiftable ring arranged in said chamber and surrounding the rotor, said ring having a substantially circular track which when the ring is in a neutral position, is substantially concentric with the periphery of said rotor, fluid conducting passageways opening into said chamber at one end portion of said rotor and at diametrically opposite sides of said ring, said rotor being provided with radial slots, a pair of vanes slidably mounted in each of said slots, the vanes of each pair being substantially identical and each provided at its inner end with a deep step and a notch of less depth than the step, the step of each vane of a pair confronting the notch of the other vane of that pair, and circular resilient means arranged in the rotor and extending into said notches for maintaining the outer ends of the vanes in contact with said track.
